GEORGE E. NICHOLSON, OF TULSA, OKLAHOMA, ASSIGNOR TO VENDING MACHINE CORPORATION OF AMERICA, OF TULSA, OKLAHOMA, A CORPORATION OF DELAWARE

COIN CONTROLLED LOCKING MEANS

Original application filed October 21, 1929, Serial No. 401,207. Divided and this application filed September 3, 1930. Serial No. 479,539.

This invention relates to improvements in vending machines, especially in coin controlled locking means therefor, and it consists of the constructions, combinations and arrangements herein described and claimed.

An object of the invention is to provide coin controlled locking means which has as its outstanding feature a slug eliminator which prevents the operation of the vending machine by subterfuges, as a perforated slug, wrapped coin of a lower denomination than that which should be inserted, etc.

Another object of the invention is to provide a rack and pawl arrangement respectively associated with certain coin and base plates for the purpose of compelling a full stroke of the coin plate for the dispensation of goods and the prevention of successive strokes of the coin plate with a view of making one coin responsible for more than a single dispensation.

Other objects and advantages will appear in the following specification, reference being had to the accompanying drawings, in

which:

Figure 1 is a plan view of so much of a vending machine as illustrates the general arrangement of the coin and base plate and their accessories, parts being shown in section;

Figure 2 is a section, taken on line 2-2 of Figure 1, showing the dime component of the coin control in the original position;

Figure 3 is a similar view illustrating the action when a dime is inserted;

Figure 4 is a perspective view of one of the lift fingers of the coin control;

Figure 5 is a detail side elevation of the slug eliminator for the dime component of the coin control;

Figure 6 is a similar view of the slug eliminator for the five-cent component of said control.

This application is a division of an application for patent for vending machine, known as Case No. 3, filed by George E. Nicholson, October 21, 1929, Serial No. 401,207. That application embodies structure of which the instant locking means is a part. So much of the vending machine

structure as is necessary to an understanding of the subject of this application is briefly described as follows:

A base 1 of hollow construction contains all of the necessary mechanism, especially the coin controlled locking means illustrated in Figure 1. A plunger 6 is slideable in respect to the base for the convenience of which the exposed end is fitted with a button 7. This is pushed on when it is desired to make a purchase.

Connected with the plunger is a coin plate 8 that partakes of every movement of the plunger. The coin plate has an upstanding lug 9 that is secured at 10 to an arm 11 which is part of a certain selector plate bracket (not shown). A push on the button 7 will slide the coin plate 8 by means of the connections 9, 10, 11 and the sliding movement is transmitted to the foregoing selector plate bracket preparatory to the dispensation of an article. The arm 11 is clamped to the plunger 6 by means of the nuts 15 that are screwed on the threaded part 14 of the plunger.

Coin receivers 25, 26, comprising forward extensions of the coin plate 8, are intended to have the coins inserted therein. The coin plate 8 is slideable on the top of a base plate 119 which is fixed upon the base 1. The forward portion of the base plate projects through a slot 120 (Figures 2 and 3) in a front cover plate 121 providing a shelf 122 upon which the receivers 25, 26 appear (Figure 1) when the plunger 6 is in the foremost position.

These receivers have holes 123, 124 respectively for the reception of a dime and five-cent piece. The purchaser must insert these coins in the holes and then push in on the button 1 in making the purchase. Guides 127 slidably receive the lateral edges of the coin plate 8. These guides are secured to the base plate 119.

The coin control occurs at this point. It comprises a simplified construction for causing operation of the machine when the proper combination of coins is inserted in the holes 123, 124 and for selecting between good coins and slugs. The latter are usually perforated with a central hole of a suitable size for the

purpose of preventing persons passing them as coins, and it is slugs of this type that will not operate the machine even though they be identical both in diameter or thickness with either a dime or five-cent piece.

- 5 The coin plate 119 has a passage 128 opening at the rear or inner edge. One side of the passage is serrated at 129 to provide a rack with which a pawl 130 is engageable to prevent a premature retraction of the plunger 6 as well as a second inward movement of the plunger without inserting other coins in the receivers 25, 26. In the first instance the purchaser is compelled to push the plunger 6 all the way in and is thus assured that he will get his goods. In the second instance he is prevented from repeatedly working the plunger to deliver more goods than he is paying for.
- 10 This pawl 130 stands at the open end of the passage 128. It is pivoted at 131 to the base plate 119. A light spring 132 is connected with the pawl at one side of the pivot and with a suitable stud either on the base 15 plate or some other fixed part in order to keep the pawl in the position in Figure 1.

There is a permissible but limited initial movement of the plunger 6 and coin plate 8. The extent of this permissible movement is 20 insufficient to permit engagement of the pawl 130 with the first or innermost tooth of the rack 129. It is only when the proper coins are inserted in the holes 123, 124 that certain locking hooks 133, 134, forming part of the 25 foregoing vending machine, will be raised to enable a sufficient inward movement of the coin plate 8 to bring the rack 129 into registration with the pawl 130.

Spacer sleeves 140 not only keep the locking hooks 133, 134 in the proper position, but serve the same purpose for a pair of lift fingers 141, 142. The lift fingers have inwardly directed tongues 143, 144 with which screws 145 of the hooks 133, 134 engage so 40 that the lifting of the fingers 141, 142 will lift the hooks 133, 134.

A guide plate 147 (Figure 1) has slots 150 (Figures 2 and 3) in which the ends of the fingers 141, 142 work. Slots 151 in the slideable coin plate 8 coincide with similar slots 152 in each of a pair of spring plates 153, 154. These spring plates are secured at 50 to the cover plate 121 and are disposed immediately above the coin plate 8. In other words, the spring plates 153, 154 are spaced from the base plate 119 (Figure 3) and the coin plate 8 slides between the two.

The inner ends of the spring plates 153, 55 154 are reduced to tongues 156 (Figure 2) which are bent downwardly and rearwardly and are sufficiently narrow to occupy the slots 151 thus to engage the under sides of corresponding tongues 157 bent forwardly and 60 upwardly from the base plate 119 and also

sufficiently narrow to occupy the slots 151 of the movable coin plate 8.

It is the purpose of the combined tongues 156, 157 to insure the ejection of a coin stuck in the coin holes 123, 124 intentionally or otherwise. Should a coin be wedged in a hole it will ultimately ride upon the downwardly projecting tongue 156 (dotted lines Figure 3), and thus be pried loose so that it will fall into a money drawer 106.

70 Openings 158, 159 (Figure 2) provide in the base plate 119 places where either full-size or under-size coins will fall through. The openings 159 are smaller than the openings 158 and are situated in advance thereof. These openings are connected by slots 160 in which slug eliminators 161 and 162 hang and swing. These eliminators resemble bell cranks (Figures 5 and 6). They are pivoted at 161^a to the respective lift fingers 80 141 and 142.

Normally the slug eliminators hang down perfectly free (Figure 2), but upon presentation of good coins thereto (Figure 3) the heels 163 will ride upon the coins causing the lifting of the lift fingers 141, 142 and the consequent raising of the hooks 133, 134. In order to impart resiliency to the lift fingers so that they may yield to a limited degree, especially when new money of original 90 thickness is inserted in the machine and passes under the slug eliminators, these lift fingers are given double twists to produce horizontally flat places 164.

95 There is a slight difference in construction 100 between the dime slug eliminator 161 (Figure 5) and the five-cent slug eliminator 162 (Figure 6). In the latter the heel 163 is offset from the pendent end 165 somewhat more than is the heel 163 of the eliminator 161. The space 166 is therefore somewhat greater in one eliminator than the other.

105 The foregoing difference is made necessary by the inherently different thickness of dimes and five-cent pieces. The slightly 110 greater spacing of the heel of the eliminator 162 adapts it to a five-cent piece when the latter is in a contacting position whereas if the eliminator 161 were used in lieu thereof there would be an undesirable wedging of 115 the coin and excessive flexure of the lift finger 142.

120 The operation is readily understood. The operation of the vending machine is predicated on the insertion of a dime and a five-cent piece in the holes 123, 124 of the receivers 25, 26. The button 7 is pushed upon to start the vending operation.

An inward push of an extent sufficient to displace the pawl 130 (Figure 1) and cause 125 it to engage with the first teeth of the rack 129 will also bring the coins under the slug eliminators 161, 162 (Figure 3). The lift fingers 141, 142 are thus raised, with a consequent raising of the hooks 133, 134 as previ- 130

ously brought out. When the latter are raised the operator is enabled to push the button 7, consequently the coin plate 8 all the way toward the completion of the vending operation.

Sometime during the inward push of the button 7 the coins will drop out into the coin drawer 106 by virtue of meeting the tongues 156 (Figure 3). Should the purchaser insert a slug with a central hole the rim of the slug would ride under the heel 163 and cause the heel to enter the hole. The result would be a mere partial turning of the slug eliminator and not that raising of the respective lift finger essential to the raising of its locking hook.

While the construction and arrangement of the improved coin controlled locking device is that of a generally preferred form 20 obvious modifications and changes may be made without departing from the spirit of the invention or the scope of the claims.

I claim:

1. In a vending machine, a movable lift 25 finger, guide means for the lift finger, a slug eliminator carried by the lift finger, a coin receiver to introduce a coin beneath said eliminator to move the lift finger, and flexible means incorporated in the finger enabling 30 yielding when limited in movement by the guide means.

2. In a vending machine, a coin control including a slug eliminator, guide means, a lift finger carrying said eliminator, and a 35 coin receiver to introduce a coin beneath said eliminator, said finger then being guided by the guide means when lifted by said coin, said lift finger having a flattened portion imparting flexibility.

40 3. In a vending machine, a slotted coin plate, a slotted base plate on one side of the coin plate, a spring plate on the other side of the coin plate, and tongues on the respective base and spring plate to be oppositely directed through the slot of the coin plate to assume confronting positions.

4. In a vending machine, a base plate having a pair of coin openings with a connecting slot, locking means, actuating means for the 50 locking means, a coin plate movable over the base plate, and a slug eliminator suspended from the actuating means in the slot and in the path of a coin carried by the coin plate.

5. In a vending machine, a base plate having a pair of coin openings with a connecting slot, a coin plate movable over the base plate, locking means for the coin plate, actuating means for the locking means, and a 55 slug eliminator pivotally carried by the actuating means, said slug eliminator comprising a pendent end normally occupying the slot adjacent to one of the coin openings, and a heel offset from the pendent end being normally clear of both the slot and said adjacent 60 opening.

6. In a vending machine, the combination of a slotted base plate, a slotted plate spaced therefrom, a coin plate, movable in the space between said plates also having a slot and a coin hole, all of the said slots being in registration, locking means to lock the coin plate, actuating means operative on the locking means to release the coin plate, and means carried by the actuating means, extending through the registering slots in the path of the coin preparatory to engagement for acting on the actuating means.
